UNITED STATES PATENT OFFICE.

JOHN M. ALLEN, OF TORONTO, ONTARIO, CANADA.

METHOD OF MAKING HOSIERY.

Application filed April 9, 1925. Serial No. 21,989.

To all whom it may concern:

Be it known that I, JOHN M. ALLEN, a subject of the King of Great Britain, and resident of the city of Toronto, county of York, Province of Ontario, in the Dominion of Canada, have invented certain new and useful Improvements in a Method of Making Hosiery, as described in the following specification and illustrated in the accompanying drawings, that form part of the same.

It has been proposed to manufacture a double stocking, that is, to arrange one stocking within another and to secure them together by seaming or stitching.

The principal object of providing such a stocking is to enable silken hosiery being worn in cold weather without discomfort and to allow of the use of silken hosiery by persons who cannot wear silk next to the foot, and further to provide such a stocking of very neat and attractive appearance, which will have extraordinary wearing qualities.

The principal features of the invention consist in the novel manner of joining the two elements of the composite stocking together so that there will be no heavy, ungainly or cumbersome seams and particularly that the circumferential flexibility of the stocking will not be impaired or unduly restricted.

In manufacturing stockings according to the present method, a circular knitting machine is used and a dial is arranged at the top of the cylinder provided with a plurality of radial guide-ways in which are arranged radial fingers adapted to be extended into the path of movement of the needles and to be withdrawn therefrom in order to provide means for attaching the two stockings together.

In the accompanying drawings, Figure 1 is a perspective view of a portion of the head of a circular knitting machine showing the device for holding certain stitches as required in the present method.

Figure 2 is an enlarged detail view showing the method of holding the stitch loops out of action during the required period.

Figure 3 is a perspective detail of a portion of a stocking showing the free fabric strip by means of which the inner stocking is secured at the top to the outer stocking, the strip being shown cut and partly turned up.

Figure 4 is a perspective detail of a portion of a looping machine showing the manner of loop stitching the top of the inner stocking to the free strip of the outer stocking.

Figure 5 is an enlarged detail showing the inner stocking attached to the outer one.

The present method is carried into effect on a standard circular knitting machine and the commencement of the stocking is the same as the commencement of any ordinary stocking.

After a few rows have been knitted, say fifteen or twenty, the radial fingers 1 carried on the disc 2 are moved outwardly by means of the operating cam 3. The alternating needles of the knitting machine pass upwardly between the pairs of fingers 1 which are peculiarly formed with outwardly bowed ends 4 formed with hooks 5 at the extremity, which hooks are bent inwardly and meet. The alternating needles pass upwardly through the openings formed between the bowed ends of each pair of fingers 80 and the thread is drawn over the hooked ends 5. The fingers 1 are then retracted by the operation of the cam and the hooked ends 5 retain the threaded loops knitted thereon.

The knitting operation then proceeds, leaving these loops strung upon the hooks as shown in Fig. 2 and the top 6 or pocket welt of the stocking is formed, being turned in the usual manner at the desired length 90 and when the knitting has progressed to form the inner part of the pocket welt to the depth of the outer part, the radial fingers 1 are again extended and the alternating knitting needles rising between the bowed ends of the fingers pick off the loops 7 and knit them into the fabric. The inner portion of the pocket welt is thus joined to the outer portion by means of the loops 7 and a strip 8 formed by the first few rows 100 of stitches is left on the bottom edge of the pocket welt 6.

The knitting then continues in the usual manner to form the outer leg and foot, preferably of a silken fabric below a cotton 105 top.

An inner stocking of cotton fabric is knitted separately and the two stockings are put together by drawing one over the other on a suitable form. They are then seamed 110 together longitudinally at the back and foot, having the stitches 9 passing through both

inner and outer stockings and firmly securing them throughout their length.

The upper edge of the inner stocking is then cast on to the points 10 of the looping machine along with the stitches of the strip 8 formed by the first few knitted rows of stitches, which is left free below the loops 7. These cast-on stitches are then joined by the regular loop stitches 11 which is a flexible stitch and which joins the edges of the strip 8 and the inner stocking without forming a double thickness or a seam. The top of the stocking is therefore formed without any circumferentially restricting element and it will stretch uniformly and will consequently be very comfortable to the wearer.

What I claim as my invention is:—

1. A method of making hosiery consisting in knitting an outer stocking with a pocket welt at the top and a fabric strip extending from the bottom of the pocket welt, and securing an inner stocking to the outer stocking and connecting the upper edge of said inner stocking to the free edge of said strip.

2. A method of making hosiery, consisting in first knitting a length of fabric, then forming a pocket welt, leaving the first knitted length of fabric free, then completing the knitting to form an outer stocking, then knitting an inner stocking, then securing the inner stocking to the outer stocking and then joining the top of the inner stocking to the free edge of the first knitted length of fabric.

3. A method of making hosiery, consisting in first knitting a length of fabric, then forming a pocket welt leaving the first knitted strip of fabric free on the inward side,

then completing the knitting to form an outer stocking, then knitting an inner stocking, then drawing the inner stocking over the reversed outer stocking, then joining the inner and outer stockings up the back with a longitudinal seam, then joining the upper edge of the inner stocking to the free edge of the first knitted fabric strip.

4. A method of making hosiery, consisting in first knitting a length of fabric, then forming a pocket welt leaving the first knitted strip of fabric free on the inward side, then completing the knitting to form an outer stocking, then knitting an inner stocking, then drawing the inner stocking over the reversed outer stocking, then securing the inner and outer stockings together, then casting a row of stitches of the free strip on to a looping machine together with a row of stitches of the upper end of the inner stocking, then loop stitching said stitches together.

5. A stocking, comprising, an outer stocking formed with a pocket welt at the top and having an integrally knitting strip of fabric at the bottom of the welt, and an inner stocking secured within the outer stocking and having its upper edge connected to the knitted strip extending below the pocket welt.

6. A stocking, comprising, an outer stocking formed with a pocket welt at the top and having an integrally knitted strip of fabric at the bottom of the welt, and an inner stocking secured within the outer stocking and having its upper edge loop stitched to the bottom edge of the knitted strip extending below the pocket welt in a connection equally elastic to the knitted fabric.

JOHN M. ALLEN.
